UNITED STATES PATENT OFFICE.

EDOUARD P. BENOIS, OF PARIS, FRANCE, ASSIGNOR TO COTY, INC., OF NEW YORK,
N. Y., A CORPORATION OF DELAWARE.

DESIGN FOR PAPER.

Application filed May 3, 1923. Serial No. 6,046. Term of patent 14 years.

To all whom it may concern:

Be it known that I, EDOUARD P. BENOIS, a citizen of France, residing in the city of Paris, Republic of France, have invented a new, original, and ornamental Design for Paper, of which the following is a specification, reference being had to the accompanying drawing, forming a part thereof.

The figure is a plan view of a piece of paper, showing my new design.

I claim:—

The ornamental design for paper as shown.

EDOUARD P. BENOIS.
